[57] **CLAIM**

The ornamental design for a display case for dispensing articles, as shown and described.

DESCRIPTION

FIG. 1 is a perspective view of a display case for dispensing articles showing our new design;

FIG. 2 is a top plan view thereof;

FIG. 3 is a front elevational view thereof;

FIG. 4 is a right side elevational view, the left side being a mirror image thereof;

FIG. 5 is a rear elevational view thereof;

FIG. 6 is a bottom plan view thereof;

FIG. 7 is an enlarged fragmentary sectional view taken along line 7—7 of FIG. 3;

FIG. 8 is an enlarged fragmentary sectional view taken along line 8—8 of FIG. 7;

FIG. 9 is a top plan view of a second embodiment of the display case for dispensing articles shown in FIG. 1;

FIG. 10 is a front elevational view thereof;

FIG. 11 is a right side elevational view, the left side being a mirror image thereof;

FIG. 12 is a rear elevational view thereof;

FIG. 13 is a bottom plan view thereof;

FIG. 14 is an enlarged fragmentary sectional view taken along line 14—14 of FIG. 10; and

FIG. 15 is an enlarged fragmentary sectional view taken along line 15—15 of FIG. 14.
